D3-10

AU 292 EX
OR D 20,170

UNITED STATES PATENT OFFICE.

FRANK H. LA PIERRE, OF NEW YORK, N. Y.

DESIGN FOR A PLATE FOR CANES OR UMBRELLA-HANDLES.

SPECIFICATION forming part of Design No. 20,170, dated September 23, 1890.

Application filed June 17, 1890. Serial No. 355,803. Term of patent 3½ years.

To all whom it may concern:

Be it known that I, FRANK H. LA PIERRE, a citizen of the United States, residing at New York, in the county of New York and State of New York, have invented a certain new Design for a Plate for Umbrellas or Canes, of which the following is a specification.

My present invention consists of a design for a plate to be used on umbrella-handles or canes.

The accompanying photograph is a face view of a plate showing the design.

The design is formed on an oblong silver or other metallic plate of the general form shown in the photograph, and of the proper length to be curved spirally around or nearly around the handle of an umbrella or a cane. As shown, the plate has tapering ends with its central portion or body made much wider to provide a space for a series of raised letters, as shown in the photograph. This central space is surrounded by an ornamental raised border, consisting of a series of curved conventionalized leaves or portions of plants or flowers, and the two ends beyond the inclosed central space are composed of or covered with raised ornaments of the kind described, and as shown by the photograph. The inclosed central space is ornamented by a series of raised let-

ters, these preferably being arranged to form words composing some poetical or literary quotation, as illustrated in the accompanying photograph. This feature or part of the design does not consist in the particular characters or words used, as they may be varied to suit the fancy of individuals and still present the same general appearance—that is, of having the space inclosed by the raised border ornamented by the raised characters or words.

It is obvious that the style of the border may be varied more or less, provided it retains the general appearance shown, and that any letters or words desired may be used, the gist of my design being the oblong plate provided with a raised ornamental border, inclosing a central space having raised letters or characters thereon, substantially as shown in the accompanying photograph.

I claim—

The design for an ornamental plate for canes or umbrellas, substantially as herein shown and described.

In witness whereof I hereunto set my hand in the presence of two witnesses.

FRANK H. LA PIERRE.

Witnesses:

G. A. HENCKEL,
W. H. BROWER.
